UNITED STATES PATENT OFFICE.

ACHILLE F. RAYMOND, OF GRENOBLE, FRANCE, ASSIGNOR TO CONSOLIDATED FASTENER COMPANY, A CORPORATION OF MAINE.

FASTENER.

No. 905,456.

Specification of Letters Patent.

Patented Dec. 1, 1908.

Application filed May 3, 1905. Serial No. 258,613.

To all whom it may concern:

Be it known that I, ACHILLE F. RAYMOND, a citizen of France, and resident of Grenoble, France, have invented a new and useful Improvement in Fasteners, of which the following, taken in connection with the accompanying drawings, is a specification.

My invention relates to fasteners and more particularly to the construction of a resilient ball or stud member adapted to cooperate with a socket member of any suitable type, the two constituting what is now well known as a snap fastener.

My invention consists in certain novel parts and arrangement of parts as will hereinafter appear, and the objects are to produce a fastener of superior qualities and simplicity of construction, and further to produce a construction with which the size of the hole in the material to which the stud or ball member is applied may be reduced in area.

I will first describe a resilient ball or stud embodying my invention and then point out the novel features in claims.

Figure 1 of the accompanying drawings shows in vertical cross section a ball or stud member embodying my invention, the parts thereof shown in their position prior to and ready for attachment to the material. Fig. 2 shows a vertical cross section of the stud or ball shown in Fig. 1, but taken on a plane at right-angles to plane of Fig. 1. Fig. 3 shows a vertical cross section similar to Fig. 1 but after the parts have been assembled and secured to the material. Fig. 4 shows a view of the blank before the hemispheres hereinafter described are struck up.

Similar letters of reference designate corresponding parts in the several figures of the drawings.

The elastic or resilient head of the ball or stud shown in the accompanying drawings consists of two hemispheres *a* formed of struck up brass, and both of which are integral with the horizontal part *b* from which they have been folded back. The horizontal part *b* also has integral with it two laterally extended tongues *c* through which the part *b* and hemispheres *a* are secured to the other parts of the fastener. By referring to Fig. 2 it will be seen that the tongues *c* are held between the upper and

lower flanges of a collet *d*. Also held within the flanges of the collet *d* is a member *e* 55 which may be termed a holding disk, and which is preferably inclined downwardly from its outer periphery towards the middle and may have a lip *f*, the purpose of which is to penetrate into the hole pierced 60 in the leather fabric or other material to which the ball or stud is to be applied.

The ball or stud is set or secured in place by means of an eyelet which is flanged at *h* and further provided with a struck up shank 65 or dome *m* which is closed at the top.

To apply the ball or stud above described to the material the struck up portion *m* of the riveting eyelet may first be inserted into the hole in the material and then forcibly 70 pressed into engagement with the parts above the material whereby the part *m* as shown in Fig. 3 impinges against the part *b* and becomes flattened, and at the same time enlarged, so as to form a kind of circumferential distended pad in the interior, between the part *e* on the one hand and the parts *b* and *c* on the other hand.

What I claim as my invention is:

1. A fastener stud comprising in combination, two opposed hemispheres integral with a laterally extended base, a holding disk, a collet securing together the base and holding disk and a flanged and domed attaching eyelet adapted to be spread by pressure against the base of said hemispheres, the said parts arranged and combined substantially as and for the purposes described. 80

2. A resilient fastener stud comprising in combination, an integral part having two 90 hemispheres and lateral extensions, a holding disk secured to and below said extensions and a closed top flanged attaching eyelet passed through the material from the opposite side and spread laterally above said 95 disk to secure the parts to the material, substantially as described.

In testimony whereof, I have signed my name to this specification in the presence of two subscribing witnesses, on this 13th day 100 of April A. D., 1905.

ACHILLE F. RAYMOND.

In presence of—

A. DEGHANY,
E. DEMIND.
